CONTROL OF GRID GLOW TUBES

Application filed January 23, 1929. Serial No. 334,451.

Our invention relates to control circuits and more particularly to control circuits comprising a grid glow tube.

An object of our invention is to provide a relatively simple and direct control system that shall embody a light-sensitive means as the primary control element and that shall embody a grid glow tube as an immediate controlling means for a work circuit, an indicating or a signal device, or, in fact, any energy-translating device.

In practicing our invention, we provide in a specific form thereof in combination with a work circuit, a contactor for controlling the same, the actuating coil of the contactor being controlled by a grid glow tube. The grid glow tube is, in turn, controlled by the variation in the energization of one or more of a plurality of photo-electric cells.

20 In the single sheet of drawings,

Figure 1 is a diagram of connections of a system embodying our invention,

Fig. 2 is a diagram of connections of a modified system embodying our invention,

25 Fig. 3 is a diagram of connections of another modification embodying our invention, and

Fig. 4 is a diagram of connections of a still further system embodying our invention.

30 Referring more particularly to Fig. 1 of the drawings, we have there illustrated a grid glow tube 11 connected in series electric circuit with the actuating coil 12 of a contactor 13 and with a current-limiting resistor

35 14. The tube 11 comprises an anode 16, a cathode 17 and a control electrode 18, all located within a suitable casing 19.

The grid glow tube, illustrated in general only, is of the type in which the superficial area of the cathode 17 is large and in which

40 the anode 16 is relatively very small, both in volume and in superficial area. The control electrode 18 is also relatively very small in volume and in area and is located relatively

45 very close to the anode 16.

A tube or electrical-discharge device of this kind has the property of being substantially non-conducting, so long as the control electrode 18 is completely insulated relative-

ages below an upper critical value. When the anode and the cathode are connected to a suitable source of supply of electric energy, the voltage of which is below this critical value, which, in this particular embodiment of our invention, is a battery 21, providing a direct-current potential, the action of the tube is such that a blocking electro-static charge accumulates on the control electrode and prevents a current of any substantial value traversing the tube, so long as the control electrode is insulated, as described above.

If, however, the control electrode be momentarily connected to the anode either directly or through a leakage impedance path of suitable value, the blocking charge will be dissipated, and the tube will become electric-conducting substantially instantaneously.

It is to be noted that the tube has, inherently, a fully conducting and substantially non-conducting condition only as regards the direct control of a relay coil, or of an energy-translating device of any kind operatively associated with the grid-glow-tube circuit and that it does not have any intermediate variable operating condition, such as does a thermionic amplifier tube.

An impedance 22, which is preferably made adjustable and may comprise an inductance, a capacitance, or a resistance or any combination thereof is connected between the anode 16 and the control electrode 18. For the apparatus shown in Figs. 1 and 3, a resistance of approximately 100 megohms is preferably used, while for the apparatus shown in the other two figures, the capacity or inductance used should have a value of sufficient magnitude to yield this impedance for the frequency of the exciting potential.

It is interesting to note that variations in the magnitude of the impedance 22 vary the voltage required to cause a discharge in the grid glow tube. Since the break-down voltage depends on the photo-cell illumination, it is possible, by varying the impedance, to vary the sensitivity of the whole system. A plurality of light-sensitive or photo-electric cells 23 are connected in circuit in series relation to each other, and the anode of one of

the cells is connected to the control electrode 18 of the glow tube. The cathode of the last cell in the series is connected to the negative terminal of the battery 21, as well as to one terminal of the actuating coil 12.

A supply circuit 24 is illustrated as embodying a plurality of conductors, a source of supply 26 of electric energy and a contact-bridging member 27 actuated by a core member 28 which is energized by the coil 12. It is to be understood that since any type or kind of work circuit indicating an energy-translating device is represented by the relay 13, no specific illustration thereof is believed to be necessary.

A source of radiant energy for the photo-sensitive cells 23 comprises an incandescent lamp 29, a source of supply 31 therefor and a control switch 32, which may be manually actuated.

Referring more particularly to Fig. 2 of the drawings, we have there shown a grid glow tube 11 connected in series-circuit relation to a current-limiting resistor 14 and an actuating coil 12, and connected across the terminals of the secondary winding 33 of an alternating-current transformer 34 embodying, in addition to the secondary winding 33, a core member 36 and a primary winding 37.

The photo-sensitive cells 23 are connected, in this modification, between the control electrode 18 and the anode 16, while the impedance 22 is connected between the electrode 18 and the junction point of the actuating winding 12 and of the secondary winding 33. A similar source of radiant energy 29 is provided, as hereinbefore set forth in connection with Fig. 1 of the drawings.

Referring more particularly to Fig. 3 of the drawings, we have there illustrated a plurality of photo-sensitive cells 23 connected in the circuit in parallel relation to each other, the other elements and the connection thereof being the same as hereinbefore set forth in connection with Fig. 1.

Referring more particularly to Fig. 4 of the drawings, we have there illustrated substantially the same elements as are shown in Fig. 2 of the drawings, with the exception that the photo-electric cells 23 are connected in the circuit in parallel relation to each other instead of in series electric-circuit relation. All the other elements of the system and circuit are substantially the same.

Referring now to Figs. 1 and 3 of the drawings, when a grid glow tube of the kind preferred by us and hereinbefore described is connected in the manner shown, and as long as the photo-electric cells are energized by the light source 29, the grid glow tube will be non-conducting so that substantially no current will traverse it, the resistor 14 and the actuating coil 12. The work circuit will, therefore, be normally deenergized.

It may be well to briefly set forth the reason for the grid glow tube being substantially electrically non-conducting. It may be noted that a shunt circuit is established thereto, beginning at the positive terminal of the battery 21, through the impedance 22 and the energized photo-electric cells 23, to the other terminal of the battery. A current of a predetermined value will traverse this circuit, and a certain potential drop will exist across the impedance 22 so that the voltage at the lower terminal thereof and, therefore, at the control electrode 18, will be lower than the potential of the anode 16. This is the condition which must exist to accumulate a blocking charge on the control electrode, and the tube is therefore non-conducting.

Since the impedance 22 is constant, the drop in potential across this impedance and, consequently, the drop in potential between the anode 16 and the control electrode 18 is determined by the current that flows in the impedance and increases with an increase in current.

The potential of the anode 16, on the other hand, is invariant and, as a consequence, an increase in the current through the impedance 22 causes a decrease in the potential of the control electrode 18, that is to say, it causes a decrease in the force tending to draw electrons from the anode.

For a large enough value of the impedance current, the potential of the control electrode is rendered so low that current is not drawn from the anode. Such a state of affairs exists when the photo-cells are under the influence of total light flux sufficient to reduce this impedance to the requisite value.

On the other hand, if the radiant energy impinging on one or more of the photo-cells is decreased in value, the impedance of the cell is increased, the current through the impedance decreased, and the potential of the control electrode is increased. For a sufficient decrease in radiant energy, the potential of the control electrode is increased enough to cause an electric breakdown of the glow tube.

The tube will then become fully conducting and the actuating coil 12 will be energized, whereby the work circuit 24 or its equivalent energy-translating device will be energized.

It should be noted, however, that a breakdown of the glow-tube may be regarded simply as a decrease in the impedance of the circuit shunting the photo-cell circuit and, consequently, results in a further decrease in the current in this circuit. If, then, the photo-cells are returned to their original state of excitation, the current in the photo-cell circuit is still considerably smaller than it originally was and, as a result, a discharge continues in the tube 11.

The tube will, therefore, continue in its energized and electric-conducting condition after it has been put in that condition, and

the relay 13 need not be particularly fast in order to be actuated in the proper manner. In order to render the tube non-conducting, it is necessary to reduce the supply-circuit 5 voltage to a value below the critical value, or to interrupt the circuit.

Referring to Figs. 2 and 4 of the drawings, the system there shown will operate to cause the tube 11 to be normally conducting so long 10 as the photo-electric cells 23 are suitably energized by the source 29.

Since the glow-tube and the photo-cells conduct currents in only one direction, the secondary 33 of the transformer 34 may be 15 regarded as a battery, similar in polarity to the battery 21 of Figs. 1 and 3, during its active period of operation. It should, however, be borne in mind that the polarizing voltage is only periodically applied.

20 It is seen that, for the circuit shown in Figs. 2 and 4, the lower terminal of the impedance 22 is substantially invariant, and, consequently, for an increase in current in the impedance 22, the potential of the electrode 25 18 is increased. Hence, in this case, an increase in the light flux impinging on the photo-cells results in an increase in the potential of the electrode and, consequently, the glow-tube breaks down if sufficient light is 20 supplied to decrease the impedance of the photo-cells to the requisite amount.

The work circuit, therefore, is normally closed. It is open when the radiations exciting one or more of the cells experience a decrease sufficient to cause the potential of the control electrode to drop below the blocking point, thus causing the tube to become non-conducting. This state of affairs will 10 cause the coil 12 to become deenergized and result in a movement of the bridging member 27 to interrupt the work circuit.

On the other hand, since the potential producing the discharge is, for the apparatus shown in Figs. 2 and 4, periodically zero for a certain interval of time, it is possible, by sufficiently decreasing the radiant energy impinging on the cells, to extinguish the glow tube.

One of the uses of a system of the kind shown in Fig. 2 is for the examination of moving objects or for the supervision of a space in which smoke and fire may occur, as in a smoke recorder. If smoke should be generated between the light source 29 and one or more of the cells 23, they would be deenergized to a greater or lesser extent and, if sufficiently deenergized, the tube would become electrically non-conducting, as explained above. As the smoke may be of momentary duration only, it is necessary that the relay 13 be very fast in its operation, in order that it may operate in the relatively short period of time in which a change in the electric-conducting condition of the tube exists.

Referring more particularly to Fig. 3 of the drawings, we have there shown a system of the same general kind as described hereinbefore in connection with Fig. 1 of the drawings, except that the photo-sensitive cells are connected in parallel, and a change in the electrical potential of the electrode 18 is effected by varying the intensity of the radiant energy reaching one or more of the shunt-connected cells. If, for instance, one 70 of the cells becomes electrically non-conducting because of the inter-position of smoke or an opaque or substantially opaque object, the conditions existing in the shunt circuit may be varied sufficiently thereby to cause the tube 11 to become electric-conducting. The impedance 22 is made adjustable in order that the circuit may be adapted to the particular conditions attendant upon the use of a plurality of parallel-connected photo-sensitive 75 cells, as well as to the actual operating conditions.

Referring to Fig. 4 of the drawings, the action of this system is substantially the same as was hereinbefore set forth in connection with Fig. 2 of the drawings and as modified by the parallel connection of the photo-sensitive cells.

It may be noted also, that the systems illustrated in Figs. 3 and 4 may also be operated with the light-sensitive cells normally deenergized when an alternating-current source of energy is used. This would be the case if a moving web of opaque material were 90 being examined for openings therein or for a break such as may occur in paper manufacture.

The system of Fig. 3 will operate on an alternating-current source with the grid glow tube normally electric-conducting, and it 100 would become non-conducting upon energization of one or more of the cells 23, and the relay or its equivalent energy-translating device would be actuated by the change in the condition of the grid glow tube.

The grid glow tube, in the system shown in Fig. 4, when connected to an alternating-current source, would be non-conducting if all of the cells 23 were deenergized, and the tube would become conducting upon energization of any one or more of the cells 23. A work circuit or energy-translating device would then be actuated or controlled by such 110 change of condition.

It may be further noted that it is not necessary that a single source of energy be provided for both the grid glow tube and the light-sensitive cells, or that the voltage of the source be the source for both elements named above. Thus, a tap 41 may be provided on the battery 21, shown in Figs. 1 and 3, and the cell or cells may be connected to the tap instead of to the end one of the series of battery cells.

120 It may be noted that, when a direct-current 130

source of energy is used, it is not necessary to have an extremely fast operating relay, as the system, or particularly the tube, is non-reversible, that is, once it becomes conducting it remains so until a major change is made in the outside or in the inside conditions of the circuit.

The use of the adjustable impedance 22, connected as shown, permits of controlling 10 the sensitivity of the tube so that minor variations in the electrical conditions of the circuit or in the operating conditions will not effect a change in the condition of the tube, except and unless such changes be of the 15 proper magnitude of which it is desired to take cognizance.

When an alternating-current source of energy is used, the relay should be extremely fast, particularly if the operation supervised 20 by the system is such as to inherently permit of very fast, abnormal operating conditions which are to be recognized in the work circuit.

A grid glow tube of the kind illustrated 25 and described, permits of being traversed by a current on the order of milli-amperes and, therefore, it is unnecessary to use a thermionic amplifier tube, as has been done heretofore, our circuits thus being relatively 30 much more simple and more rugged and effecting the same control in a somewhat different manner.

We desire it to be understood that when 35 the term—"energy-translating device" is used in the claims, any controllable means—such as a relay or a signal device actuatable by electric current, is included.

Various modifications may be made in the 40 system embodying our invention without departing from the spirit and scope thereof, and we desire, therefore, that only such limitations shall be placed thereon as are imposed by the prior art or are set forth in the appended claims.

15 We claim as our invention:

1. In an electric circuit, in combination, 50 an energy-translating device, a glow tube having two main electrodes and a control electrode and having inherently a fully conducting and a substantially non-conducting condition only, means for connecting the main electrodes and the energy-translating device in electric circuit with a source of electric energy, means for controlling the 55 energization of said energy-translating device and tube comprising a series-connected impedance and a plurality of light-sensitive cells, means for connecting the junction of the impedance and the cells to the control electrode, and the outer terminals of another of the cells and the impedance to the 60 respective main electrodes.

2. In an electric circuit, in combination, 65 an energy-translating device, a glow tube having, inherently, a fully conducting and

a substantially non-conducting operating condition only and embodying two main electrodes and a control electrode, means for controlling the operating condition of said tube comprising a plurality of light-sensitive cells electrically connected to the control electrode and one of the main electrodes, and means for controlling the sensitivity of the glow tube comprising an impedance electrically connected to the control electrode and 70 the other main electrode.

3. In an electric circuit, in combination, an energy-translating device, a glow tube having, inherently, a fully conducting and a substantially non-conducting operating condition only and embodying two main electrodes and a control electrode, means for controlling the operating condition of said tube comprising a plurality of light-sensitive cells electrically connected to the control electrode and one of the main electrodes, and means cooperating with said cells to effect a change 80 in the operating condition of said tube only upon the occurrence of a change of predetermined magnitude in the electrical condition 85 of one or more of said cells, said means comprising an impedance electrically connected to the control electrode and the other main electrode.

4. In an electric circuit, in combination, an energy-translating device, a glow tube connected in electric circuit with said energy-translating device and embodying two main electrodes and a control electrode and having, inherently, a fully conducting and a substantially non-conducting operating condition only, and control means for said tube comprising a plurality of series-connected light-sensitive cells, means for electrically connecting them to the control electrode and one of the main electrodes, an impedance, and means for electrically connecting it to the control electrode and to the other main electrode.

5. In an electric circuit, in combination, 110 an energy-translating device, a glow tube having two main electrodes and a control electrode and having inherently a fully conducting and a substantially non-conducting condition only, means for connecting the main electrodes and the energy-translating device in electric circuit with a source of electric energy, means for controlling the energization of said energy-translating device and tube comprising a series-connected impedance 115 and a light-sensitive device, means for connecting the junction of the impedance and the light-sensitive device to the control electrode, and the outer terminals of the light-sensitive device and the impedance to the respective main electrodes.

6. In an electric circuit, in combination, an energy-translating device, a glow tube having, inherently, a fully conducting and a substantially non-conducting operating condition only and embodying two main electrodes 120

and a control electrode, means for controlling the operating condition of said tube comprising a light-sensitive cell electrically connected to the control electrode and one of the main electrodes, and means cooperating with said cell to effect a change in the operating condition of said tube only upon the occurrence of a change of predetermined magnitude in the electrical condition of said cell, said means comprising an impedance electrically connected to the control electrode and the other main electrode.

7. In an electric circuit, in combination, an energy-translating device, a glow tube having, inherently, a fully conducting and a substantially non-conducting operating condition only and embodying a cathode, an anode and a control electrode, means for controlling the operating condition of said tube comprising a light-sensitive cell electrically connected to the control electrode and the cathode, and means cooperating with said cell to effect a change in the operating condition of said tube only upon the occurrence of a change of predetermined magnitude in the electrical condition of said cell, said means comprising an impedance electrically connected to the control electrode and the anode.

In testimony whereof, we have hereunto subscribed our names this 18th day of January, 1929.

JOHN VICTOR BREISKY.
ELLIS O. ERICKSON.
